UNITED STATES PATENT OFFICE.

WILLARD F. RICHARDS, OF BUFFALO, NEW YORK.

DESIGN FOR A BRAKE-BEAM.

SPECIFICATION forming part of Design No. 25,443, dated April 28, 1896.

Application filed March 24, 1896. Serial No. 584,700. Term of patent 14 years.

To all whom it may concern:

Be it known that I, WILLARD F. RICHARDS, a citizen of the United States, residing at Buffalo, in the county of Erie and State of New York, have invented and produced a new and original Design for Brake-Beams, of which the following is a specification, reference being had to the accompanying drawings, showing a part thereof.

10 This design relates to the configuration of metallic brake-beams for railway-cars and is represented in the accompanying drawings, which form a part of this specification, and in which—

15 Figure 1 is a top plan view of a brake-beam embodying my design. Fig. 2 is a rear view thereof, partly in longitudinal section. Fig. 3 is a cross-section thereof in line 3-3, Fig. 1.

Like letters of reference refer to like parts 20 in the several figures.

The leading feature of my design consists in the taper of the beam from its middle toward its ends, raised marginal ribs extending along the front and rear edges of the beam on both sides of its web or body, and raised intermediate ribs arranged on opposite sides of the web and extending obliquely from the middle of the beam toward its ends.

25 A represents the central longitudinal web or body of the beam, which tapers or diminishes in width from its middle toward its ends and which has straight-sided end portions B.

c represents the raised ribs or flanges extending along the front edge of the beam on opposite sides of the web A, and d the raised 35 ribs or flanges extending along the rear edge of the beam on opposite sides of the web.

e represents raised oblique ribs or flanges arranged between the front and rear marginal ribs c d on opposite sides of the web and 40 extending from the middle portion of the rear marginal ribs d to the end portions of the front marginal ribs c. The front and rear sides of the straight end portions B are flush with the edges of the raised ribs c, d, and e, 45 as shown in Fig. 2.

f f represent convex ribs or semicircular bulges extending across the middle portion of the web A on opposite sides thereof. g represents similar ribs or bulges extending across 50 the web near the straight - sided end portions B.

h are openings in the web A.

What I claim is—

The design for a brake-beam, substantially 55 as herein shown and described.

Witness my hand this 18th day of January, 1896.

WILLARD F. RICHARDS.
